United States Patent Office

Des. 223,809
Patented June 13, 1972

223,809

CARTON FOR GLASSES

Richard K. Oglesbee, Lancaster, Ohio, assignor to Anchor Hocking Corporation, Lancaster, Ohio

Filed Sept. 17, 1970, Ser. No. 25,038

Term of patent 14 years

Int. Cl. D9—03

U.S. Cl. D9—176

FIG. 2

FIG. 3

FIG. 4

FIG. 5

FIG. 1 is a perspective view of a carton for glasses showing my new design;

FIG. 2 is a side elevation thereof, the other side being identical;

FIG. 3 is an end elevation thereof, the other end being identical;

FIG. 4 is a top plan; and

FIG. 5 is a bottom plan.

I claim:

The ornamental design for a carton for glasses, substantially as shown and described.
